UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

LAMP-GRIP.

1,216,884.

Specification of Letters Patent. Patented Feb. 20, 1917.

Application filed August 25, 1914. Serial No. 858,540.

To all whom it may concern:

Be it known that I, GEORGE B. THOMAS, a citizen of the United States of America, and residing at Bridgeport, in the county 5 of Fairfield and State of Connecticut, have invented a certain new and Improved Lamp-Grip, of which the following is a specification.

My invention relates to lamp receptacles 10 and particularly to means for gripping the lamp to prevent its "backing out" under the influence of vibration and the pressure under which it is screwed into the receptacle.

In the accompanying drawings,

15 Figure 1 is a broken side elevation of an electric lamp socket showing my invention embodied therein in one form;

Fig. 2 is a plan of the same with the casing removed;

20 Fig. 3 is a perspective of the screw shell contact of the socket; and

Fig. 4 is a perspective of a gripping device adapted to be used in the screw shell shown in Fig. 3.

25 While the present invention is applicable to lamp receptacles of all types in which the lamp is adapted to be screwed into a socket of the Edison type, I have here shown it embodied in a pull socket having the usual 30 casing comprising cap 10, shell 11, insulating lining 12 and bell mouth 13 through which the usual pull chain or cord is led from the switch actuating device within the socket.

35 Inasmuch as the switch mechanism forms no part of my invention, it is not here shown. The center contact 14 is mounted upon the usual insulating base 15 as is also the screw shell side contact 16 into which 40 the threaded base of the lamp is adapted to be screwed. Overlying the base flanges 17 of the screw shell I have provided a reinforcing ring 18 held in position within the screw shell by means of the usual securing 45 screws 19. From the margin of the ring 18 extend downwardly a plurality (here 3) spring fingers 20 which lie inside the thread 21 on the screw shell and engage the entering base of the lamp. To permit these 50 fingers to be spread by the entering lamp base, the side wall of the screw shell 16 is

cut away to afford slots 22 in register with the spring fingers 20. Should the pressure upon the lamp base be otherwise insufficient to prevent the lamp from "backing out", I 55 provide inwardly struck prongs 23, Fig. 4, so formed that they permit the lamp base to be readily screwed into the socket shell, but provided with engaging points 24 which dig into the lamp base on its reverse rotation and thus prevent its accidental unscrewing.

The operation of the grip is obvious. As the lamp base is screwed into the socket shell 16, it engages the spring fingers 20 65 and tends to spread the latter. The spring fingers are free to yield through the slots 22 in the lamp shell and consequently permit the lamp base to be screwed home and into engagement with the center contact 70 14, while at the same time they add a sufficient frictional grip upon the base to hold it against the backing out. Where the prongs 23 are employed the frictional grip is reinforced by their engagement with the 75 lamp base. They do not however prevent the intentional removal of the lamp, since upon the exertion of sufficient force, the fingers 20 spread outward and the lamp base 80 may be unscrewed.

Various modifications embodying my invention will readily suggest themselves to those skilled in the art and I do not limit my invention to the precise embodiment 85 here shown and described.

I claim as my invention:—

A lamp receptacle comprising a screw shell side contact of the Edison type, and an independent lamp grip device lying within said screw shell and having a base resting 90 against the base of the screw shell and spring arm means extending outward toward the lamp receiving end of the receptacle to grip an inserted lamp base, substantially as described.

In testimony whereof I have signed my name to this specification, in the presence of two subscribing witnesses.

GEORGE B. THOMAS.
